SEWING CABINET

Patrick H. Harmon, San Fernando, Calif.

Application May 23, 1936, Serial No. 81,529

6 Claims. (Cl. 223—107)

My invention relates to improvements in work boxes for use more particularly as a sewing cabinet although it may be used in other capacities as will presently appear.

5 The invention is designed primarily to provide a cabinet of the folding sectional type which embodies a pair of tray sections hinged together and suspended for swinging movement into either open position to provide a pair of open top trays, 10 or, into closed position to provide a closed compartment, the sections counterbalancing each other in either of said positions against movement to the opposite position so that no catches or other locking devices are required to hold the 15 sections closed or open.

Another object is to provide a cabinet of the class and for the purpose above indicated which is simple in construction, strong and durable, and economical to manufacture.

20 Other objects are also comprehended by my invention all of which together with the exact nature of my improvements will be readily understood when the following description and claims are read with reference to the accompanying drawing:

25 In said drawing:

Figure 1 is a view in vertical section taken on the line 1—1 of Figure 2, looking in the direction indicated by the arrows, and illustrating the 30 cabinet of my invention with the sections in closed position.

Figure 2 is a view in transverse section, and

35 Figure 3 is a view partly in transverse section and partly in side elevation illustrating the sections in opened position.

Referring to the drawing in detail, and by reference numerals, the illustrated embodiment of my invention comprises a pair of opposed end uprights 1 of any suitable edge contour, connected together at their upper ends by a bar 2, shaped to provide a hand grip 3 for carrying the cabinet from place to place, and similarly connected at their lower ends by a bar 3'.

Intermediate the uprights 1 and swingingly 45 mounted thereon, as presently described, is a pair of tray sections 4 and 5, respectively, each comprising end walls 6, side walls 7 and a bottom wall 8. The trays 4 and 5 are designed so that they gradually increase in depth from one end 50 to the other and are thereby formed with large and small outer and inner ends, respectively. Preferably the bottom walls 8 of each tray are relatively divergent outwardly from the end wall 6 to facilitate access to the interior of the trays.

55 The small ends 6 of the trays 4 and 5 are hinged

together as at 9 at their open edges whereby said trays may be relatively swung to opened position determined by engagement of said small ends of the trays, or, to closed position as determined by engagement of the open edges of said trays. 5 The trays 4 and 5, in their fully opened position incline outwardly and downwardly to further facilitate access to the interior thereof in said opened position.

The trays 4 and 5 are suspended from the uprights 1, by means of opposed pair of rod-like links 10, the links of each pair being pivotally connected side by side to the uprights 1 and to the sides 7 of said trays. Preferably said links are pivotally mounted in metal plates 11 and 12 15 suitably secured to the uprights and trays, respectively, as by screws 13. The pivotal connections of the links 10 to the trays 4 and 5 are offset rearwardly of the transverse center of said trays and also offset below the longitudinal center of said trays whereby in the opened positions of said trays the greater portion of the weight thereof is outside the points of pivotal connection of the links 10 thereto. This feature provides for each tray in its opened position counterbalancing the other against movement to closed position. The pivotal points of connection of the links 10 to the uprights 1 and trays 4 and 5 are relatively arranged so that the links incline downwardly and outwardly from their 20 points of connection to said uprights whereby the points of connection of the links to the trays are always laterally offset outwardly from the center of gravity of said links. As will be clear this feature provides for the trays being urged 25 towards closing position by their own weight after they have been swung inwardly on their hinges 9 past a vertical dead center position relative to the pivotal points 10' of connection of the links 10 thereto.

40 Each tray 4 and 5 is provided with a centrally located transverse partition 14 which in the opened position of the tray inclines upwardly and outwardly to facilitate access to the rear compartment formed in the tray thereby, and in the 45 closed position of the tray inclines upwardly and inwardly so that implements or articles located on said partition will gravitate toward the outside of the tray for a purpose which will be clear. The small ends of the trays 4 and 5 are provided 50 with inwardly extending ledges 15 at their open edges which in the closed position of the trays form upright partitions for preventing the contents of the trays from intermingling.

55 It is to be noted that the described means for

suspending the trays for independent swinging movement causes them to swing up to an elevated position when moving from closed to opened position. Thus the cabinet may be built 5 low and the contents of the trays easily reached when the latter are opened.

This feature together with the described inclination of the trays and the outer end walls and partitions thereof provides for easy removal 10 of articles from the bottom thereof and for rendering articles on the bottom of the trays readily visible to a person seated alongside the cabinet.

The foregoing is a detailed description of a preferred embodiment of my invention and it is believed that the construction and advantages 15 thereof will be clear without further explanation. It is to be understood, however, that the precise details described are illustrative of a preferred embodiment of my invention only, and that right 20 is herein reserved to changes and modifications of such details falling within the scope of the claims appended hereto.

What I claim is:

1. A cabinet comprising, a pair of spaced apart 25 opposed uprights, a pair of open top trays between said uprights having end and side walls, respectively, and hingedly connected together in end to end position for folding movement into closing and opening relation, and means for suspending said trays from said uprights for relative 30 swinging movement, said means being pivotally connected to said uprights and to the sides of the trays, respectively.

2. A cabinet comprising, a pair of spaced apart 35 opposed uprights, a pair of open top trays between said uprights having end and side walls, respectively, and hingedly connected together in end to end position for folding movement into closing and opening relation, and means for suspending said trays from said uprights for relative 40 swinging movement, said means being pivotally connected to said uprights and to the sides of the trays, respectively, said means being pivotally connected to the respective trays each at points 45 so that the centers of gravity of the two trays when in closed position will lie between the two pivot connections so as to hold the trays in closed position and when in open position the individual centers of gravity of the two trays will be outward 50 of the pivotal connections thereby maintaining the trays in their open positions.

3. A cabinet comprising, a pair of spaced apart 55 opposed uprights, a pair of open top trays between said uprights having end and side walls, respectively, and hingedly connected together in end to end position for folding movement into closing and opening relation, and means for suspending said trays from said uprights for relative 60 swinging movement, said means being pivotally connected to said uprights and to the sides of the trays, respectively, said means being pivotally connected to the respective trays each at points 65 so that the centers of gravity of the two trays when in closed position will lie between the two pivot connections so as to hold the trays in closed position and when in open position the individual centers of gravity of the two trays

will be outward of the pivotal connections thereby maintaining the trays in their open positions, said trays having their hinged ends inclined upwardly and outwardly from the hinges when the trays are in closed position whereby the trays will slope 5 downwardly and outwardly from the hinges when they are in open position.

4. A cabinet comprising, a pair of spaced apart 10 opposed uprights, a pair of open top trays between said uprights having end and side walls, respectively, and hingedly connected together in end to end position for folding movement into closing and opening relation, and means for suspending said trays from said uprights for relative 15 swinging movement, said means being pivotally connected to said uprights and to the sides of the trays, respectively, said means being pivotally connected to the respective trays each at points 20 so that the centers of gravity of the two trays when in closed position will lie between the two pivot connections so as to hold the trays in closed position and when in open position the individual centers of gravity of the two trays will be outward 25 of the pivotal connections thereby maintaining the trays in their open positions, and said trays being deeper at one end than at the other and inclining outwardly and downwardly in their opened position with the hinged ends abutting and limiting the outward swinging of the trays.

5. A cabinet comprising, a pair of spaced apart 30 opposed uprights, a pair of open top trays between said uprights having end and side walls, respectively, and hingedly connected together in end to end position for folding movement into closing and opening relation, and means for suspending said trays from said uprights for relative 35 swinging movement, said means being pivotally connected to said uprights and to the sides of the trays, respectively, said means being pivotally connected to the respective trays each at 40 points so that the centers of gravity of the two trays when in closed position will lie between the two pivot connections so as to hold the trays in closed position and when in open position the individual centers of gravity of the two trays will 45 be outward of the pivotal connections thereby maintaining the trays in their open positions, said trays having, respectively, a transverse partition inclining from the bottom of the tray inwardly and upwardly in the closed position of said tray, 50 and upwardly and outwardly in the opened position of the tray and the end walls of each tray being outwardly divergent relatively.

6. A cabinet comprising, a pair of spaced apart 55 opposed uprights, a pair of open top trays between said uprights having end and side walls, respectively, and hingedly connected together in end to end position for folding movement into closing and opening relation, and means for suspending the trays from said uprights for relative 60 swinging movement comprising, opposed pairs of rod-like links pivotally connected to the uprights and to the sides of the trays, respectively, and inclining outwardly and downwardly from said uprights in either position of said trays.

PATRICK H. HARMON.
